UNITED STATES PATENT OFFICE

2,206,260

METAL CONTAINER

Robert Nyden, Long Island City, N. Y.

Application February 3, 1939, Serial No. 254,440

3 Claims. (Cl. 220—36)

The present invention relates to metal containers of the type ordinarily employed in the marketing of medicinal products such as tablets, prepared bandages, individually packaged powders, lozenges and a variety of other similar products. Such containers ordinarily include a shallow body and a cover having a depending flange embracing the side and end walls of the body, the cover being adapted to be slipped off of and onto the body and being permanently hinged to the body by a pintle which passes through a series of knuckles formed on the rear side wall of the body and the cover flange. Co-operating means on the front side wall of the body and the cover flange serves to yieldably retain the cover in closed position. To remove the cover it is necessary to grasp the container in one hand and then pry off the cover with the finger nail of the other hand. Ordinarily, considerable force is required to remove the cover, with the result that the container is jarred in the hands and the contents thereof is spilled.

The principal object of the invention is to provide an improved container of this character designed to overcome the above limitations and in which the container body and cover are hinged together in such a manner that when pressure is applied to the container adjacent the hinge at one side of the container, the other side thereof will be released. Another object of the invention is to provide such a container in which the cover is hinged to the body permanently in such a manner that upon opening of the container, the cover may be swung throughout an angle of one hundred eighty degrees (180°) with respect to the body to completely uncover the contents of the container and facilitate access thereto.

A still further object of the invention is to provide a container of this nature in which the fulcrum axis for pivotal movement of the cover on the body is well forward of the effective hinge connection between the parts so that positive opening of the container will occur with the application of but a slight degree of pressure to the container.

Other objects and advantages of the invention, not at this time enumerated, will become apparent hereinafter.

In the accompanying drawing:

Fig. 1 is a perspective view of a container constructed in accordance with the principles of the present invention, showing the cover in open position.

Fig. 2 is an end elevational view of the closed container showing the hinge construction.

Fig. 3 is a sectional view taken substantially along the line 3—3 of Fig. 2, certain parts being removed to more clearly illustrate the hinge construction; and

Fig. 4 is a fragmentary top plan view of the fully opened container.

In the drawing, a container body 10 of substantially rectangular form with rounded corners 11 includes a bottom 12 and continuous upstanding side and end walls 13 and 14 respectively.

A cover 15 conforming generally in configuration to that of the body 10 having rounded corners 11', and including a top 16 and depending side and end flanges 17 and 18 respectively, is permanently hinged to the body 10, the pivotal connection between the two parts consisting of a wire link or strap 19 which is generally of wide U-shape formation, the medial base portion of which passes through an upturned bead or knuckle 20 formed on the lower edge of the rear end flange 18. The ends of the link are turned inwardly as at 21 and extend into apertures 22 formed in the side walls 13 of the body 10. The depth of the U-shaped link 19 is slightly in excess of the distance between the apertures 22 and the rear end wall 14 of the body 10 and thus the cover 15 is free to swing about the axis of the base portion of the link 19 from the closed position illustrated in Fig. 3 to the fully open position illustrated in Fig. 4 wherein the bottom 12 of the body 10 and the top 16 of the cover 15 occupy substantially the same plane.

Locking lugs 23 and 24 formed on the front cover flange 18 and front end wall 14 respectively serve to yieldingly maintain the cover closed on the body.

Referring now to Fig. 3, it will be seen that the inturned ends 21 of the link 19 pass through the side walls 13 at points which are in the same horizontal plane and which are disposed a substantial distance below the upper edge of these side walls. When the cover is in its closed position on the body 10, the lower edges of the side flanges 17 bear against these inturned ends 21 while the top 16 remains a slight distance above the plane of the upper rim of the body 10. Because of this latter fact, when pressure is applied to the container rearwardly of the region at which the inturned ends 21 enter the side walls 13, i. e. adjacent the effective hinge connection at the rear of the container, the cover will be rocked upon the body about the common axis of the inturned ends 21 in such a manner

as to release the locking lugs 23 and 24 and permit full opening of the container.

In order to provide a container which is attractive in appearance and one which possesses no sharp raw edges or corners, the lower rim of the cover flanges 17 and 18 may be provided with a substantially continuous upturned bead 25 which at the rear of the container forms a continuation of the knuckle or bead 26 as shown in Fig. 2.

10 Modifications may be resorted to within the spirit and scope of the appended claims.

I claim:

15 1. In a metal container, a body having a vertical wall and a cover having a depending flange embracing the wall in the closed position of the cover, a substantially U-shaped link having its ends pivotally connected to the wall at opposed points thereon, there being a pivotal connection between the base portion of the U-shaped link and said cover flange, the lower edge of said flange engaging said link adjacent the ends thereof when the cover is in its closed position 20 and being pivotally supported thereon.

25 2. In a metal container, a body having opposed pairs of upstanding side and end walls and a cover having opposed pairs of depending side and end flanges embracing the side and end walls respectively in the closed position of the cover, a substantially U-shaped link having its ends 30 pivotally connected to the side walls at opposed points thereon medially of the end walls, said link

embracing a portion of each side wall and having its base portion extending coextensively with the rear end wall and spaced slightly therefrom, the rear end flange being pivotally connected to said base portion, locking lugs formed on the front end wall and front end flange and designed for cooperation in maintaining the cover closed, the lower edges of the side flanges being supported on the link adjacent the ends thereof when the cover is closed whereby the cover is tiltably supported on the body.

3. In a metal container, a body having opposed pairs of upstanding side and end walls and a cover having opposed pairs of depending side and end flanges embracing the side and end walls respectively in the closed position of the cover, there being a pair of opposed apertures in the side walls in alignment, a link partially embracing the side walls and embracing the rear end wall, the ends of said link extending into said 20 apertures, a knuckle formed on the lower end of the rear end flange embracing the medial regions of the link, locking lugs formed on the front end wall and front end flange designed for cooperation in maintaining the cover closed, the 25 lower edges of the side flanges in the medial regions thereof being tiltably supported on the ends of the link in the closed position of the cover.

ROBERT NYDEN. 30
